UNITED STATES PATENT OFFICE.

JEFFERSON D. PARK, OF TISHOMINGO, OKLAHOMA, ASSIGNOR TO (MRS.) E. E. BROWN,
OF CLARKSVILLE, TEXAS.

QUILTING APPARATUS.

1,326,776.

Specification of Letters Patent. Patented Dec. 30, 1919.

Application filed April 10, 1916, Serial No. 90,170. Renewed May 28, 1919. Serial No. 300,480.

To all whom it may concern:

Be it known that I, JEFFERSON D. PARK, a citizen of the United States, residing at Tishomingo, in the county of Johnston and 5 State of Oklahoma, have invented certain new and useful Improvements in Quilting Apparatus, of which the following is a specification.

The present invention has to do with quilting apparatus and has for its primary objects, first, to provide a foldable frame structure capable of being collapsed to occupy a minimum amount of storage space; second, to provide auxiliary fabric holding means 10 by which the preliminary operation of insertion of batting between the material to be quilted is facilitated; third, such means to be movable into an inoperative position with respect to the quilt during quilting operation; and lastly, to provide novel locking means for holding the frame in extended position.

These and such other objects as may hereinafter appear are attained by the novel construction, combination and arrangement of parts to be hereinafter specifically described and claimed. Reference will now be had to the accompanying drawings forming a part of this specification, wherein:

30 Figure 1 is a top plan view of the quilting apparatus with the material disposed upon the fabric holding rolls preparatory to insertion of the batting between the fabric layers.

35 Fig. 2 is a side elevation thereof with the parts in position ready for quilting and the auxiliary frame arranged in inoperative position as shown in full lines and operative position in dotted lines.

40 Fig. 3 is an end elevation with the parts in the relative position shown in Fig. 2.

Fig. 4 is a side elevation showing the apparatus in closed or folded position, the full and dotted lines indicating the different positions that may be assumed by the auxiliary frame.

45 Fig. 5 is a top plan view showing the quilt apron carried by one of the fabric rolls by means of which the quilting at the end of 50 quilt is facilitated.

Fig. 6 is a fragmentary detail perspective view showing the locking means for the frame.

Fig. 7 is an enlarged perspective frag-

mentary view showing more clearly the supporting means for the swinging frame.

Fig. 8 is a detail sectional view of a friction device used with this apparatus.

Throughout the following detail description and on the several figures of the drawings, similar parts are referred to by like reference characters.

Referring to the drawings and specifically describing the invention, the numerals 1 and 2 designate crossed standards constituting 65 the main quilting frame, pivotally connected together by means of the transverse bar 3. At the upper portion of the frame members 2 is journaled a fabric holding roll 4 while a corresponding roll 5 is journaled upon the 70 upper portion of the other frame members 1. Each of these rolls is provided with a crank 6, 7, and ratchet and pawl locking means 8, 9. Pivotally mounted on the pivots 10 adjacent to the fabric roll 5 is 75 what I term for the purposes of this description a swinging auxiliary frame comprising the side members 11 in the free ends of which is mounted a third fabric roll 12. This roll is also adapted to be re- 80 volved by means of the crank 13 and is also provided with locking means 14 for holding it against rotation.

It will be observed by reference to Fig. 2 that the swinging frame referred to is capable of being moved on its pivot to a position above the plane of the rolls carried by the main frame in which position said swinging frame is held by stop means 15 attached to the frame standards 1 as shown 90 most clearly in Fig. 7. The swinging frame is arranged in this superposed position when preparing the material for quilting as will be described more clearly herein- 95 after and when the actual quilting of the material is carried out said frame is swung on its pivots into the inoperative position shown by full lines in Fig. 2 where the roll 12 is below the plane of the main frame rolls hereinbefore referred to. This move- 100 ment of the auxiliary frame is also advantageous as when it is desired to fold the apparatus, because said frame may be so positioned as to occupy a close relation with respect to the main frame standards, in a 105 manner most clearly shown in Fig. 4 of the drawing.

In order to hold the frame in extended

position, I employ locking means consisting of link members 16, 17 pivotally connected to the standards 1 and 2 of the main frame, the link member 17 being offset at 18 so as to permit the movement of the standards into closed position. The links are pivotally connected at 19 and a locking element 20 is also carried by each link pivot and this locking element is freely movable 10 into pendent position most clearly shown in Fig. 6 of the drawings. The lower end of the element is notched as indicated at 21', and automatically engages with the cross bar 3 of the frame standards in which position the extension of the frame is limited and the folding of the frame members prevented. This forms a simple locking arrangement for the device and it will be apparent that it is only necessary to break the 20 joint of the links in order to disengage the link device and permit the standards 1 and 2 to be folded. When in folded position the standards are locked together by any desired means such as the hook and eye 25 vice designated 21.

Referring to Fig. 1 of the drawings and describing the use of this apparatus, the frame is arranged in its extended or open position with the fabric holding rolls in 30 spaced relation to each other. The roll 4 carries a short canvas or other fabric strip 4' having a reinforcing rod 4'' connected to its end and said end is provided with a plurality of hooks 4^a to which the quilting material is 35 adapted to be connected. In preparing the material to be quilted, the lower fabric is first connected to the hooks 4^a and wound upon the roll 4. The opposite or right hand end of the material is then connected to the 40 apron 5' secured to the fabric roll 5, said apron being provided with the attaching means 5'' similar to that described with reference to the strip 4'. With the swinging frame moved into its operative position 45 suspended over the main frame, the right hand end of the upper layer of fabric material for the quilt is attached to the strip 12' of the roll 12 of said swinging frame and completely wound thereupon. The left 50 hand extremity of this upper fabric material is now connected to the hook members 5'' of the roll 5. The material of the lower and upper fabrics is then wound upon the roll 5 from the rolls 4 and 12, respectively, 55 the filling material or batting being inserted between these layers during such winding action. It will be obvious that the preparation of the quilt in this manner is facilitated and when the material has been completely 60 wound upon the roll 5 the upper layer end is disconnected from the roll 12 and said end attached to the fastening means 4^a of the roll 4. The material is now ready for quilting and the auxiliary frame may be moved 65 from its operative to the inoperative posi-

tion pendent from its pivots as shown in Fig. 2. As the quilting operation proceeds the material is wound upon the roll 4 until the end of the quilt passes from the roll 5 and it is at this point that the advantage 70 of the relatively wide apron 5' is apparent. The quilt can be entirely unwound from the roll 5 and quilted clear to the other end of said material without the necessity of disconnecting the fabrics from the apron. 75

In order to prevent the fabric rolls of the quilting frame from too freely unwinding, I preferably provide a friction screw 22 for each journal of these rolls as clearly shown in Fig. 8 of the drawings. The friction on 80 the respective rolls may be adjusted as desired to wind more or less freely as the case may be.

It will be obvious that slight changes may readily be made in the details of construction and arrangement of parts without departing from the spirit of the invention and within the scope of the claims appended hereto.

Having thus described my invention, what I claim as new is:

1. In quilting apparatus, the combination of a main frame, a fabric carrying roll mounted at one side thereof, a winding roll mounted at the other side thereof, and an auxiliary frame movably mounted on the main frame adjacent to the winding roll being disposed above the latter at the side of the main frame when winding material upon the winding roll, said auxiliary frame 100 being movable to a position below the winding roll when unwinding material from the winding roll on to the fabric carrying roll first mentioned.

2. In quilting apparatus, the combination 105 with a main frame, spaced rolls mounted in said frame upon which a layer of fabric to be quilted is adapted to be rolled, a swinging frame mounted at one side of the main frame and movable into superposed relation to the fabric layer above mentioned during preparation of the material for quilting, stop means on the main frame with which the side of the auxiliary frame engages for holding the auxiliary frame in the superposed position during winding of material on one of the said spaced rolls and a roll on said swinging frame for holding a second layer of fabric material to permit winding thereof upon one of the rollers of the 110 main frame aforesaid, said swinging frame being displaceable from superposed position into operative position during quilting operation.

3. In quilting apparatus, the combination 115 of a main frame composed of crossed foldable members, fabric holding rolls mounted at the upper portions of said members including a winding roll, an auxiliary frame pivotally mounted on one of said cross mem- 120

bers adjacent to the winding roll, a fabric roll carried by the auxiliary frame and movable in one direction to a position adjacent to and above the winding roll when winding material therefrom onto the winding roll, and in the other direction to pendent inoperative position below the plane of the

main winding roll when unwinding material from the winding roll during quilting, and stop means normally limiting pivotal movement of the auxiliary frame in one direction.

In testimony whereof I affix my signature.
JEFF. D. PARK.
